UNITED STATES PATENT OFFICE.

SAMUEL L. NEELY, OF LONGTON, KANSAS.

GRADE-CROSSING SIGNAL.

1,299,854.

Specification of Letters Patent. Patented Apr. 8, 1919.

Application filed May 17, 1915. Serial. No. 23,691.

To all whom it may concern:

Be it known that I, SAMUEL L. NEELY, a citizen of the United States, residing at Longton, in the county of Elk and State of Kansas, have invented certain new and useful Improvements in Grade-Crossing Signals; and I do hereby declare the following to be a full, clear, and exact description of the invention, such as will enable others 10 skilled in the art to which it appertains to make and use the same.

The invention relates to improvements in grade crossing signals.

The object of the present invention is to 15 improve the construction of grade crossing signals and to provide a simple, practical and comparatively inexpensive signal of strong and durable construction designed for automatic operation in connection with 20 a train blocking system forming the subject matter of a companion application and equipped with a pair of semaphore arms operating in planes at right angles to each other and simultaneously movable in opposite 25 directions and adapted to hang clear in a vertical position at a roadway and horizontally at the track for indicating to the persons at the roadway that it is safe to cross the track and capable when a train 30 enters the block of automatically reversing their position and of hanging vertical at the track and of extending across the roadway to warn the person at the crossing of the approach of the train.

35 It is also the object of the invention to provide a signal of this character in which the semaphore arms will counterbalance each other and enable the signal to be operated with a minimum amount of power and by an 40 exceedingly small motor.

Another object of the invention is to equip the grade crossing signal with means for normally displaying a red light to the track and a white light to the roadway and for 45 changing the colors of the light to show a white light to the track and a red light to the roadway when a train enters the block and operates the signal.

The invention also has for its object to 50 provide a grade crossing signal equipped with means for opening and closing a plurality of circuits so that a certain set of circuits may be maintained in a closed condition when the signal is in its normal position 55 and another set of circuits may be closed

when the signal changes its position and opens the first set of circuits.

Another object of the invention is to provide a signal adapted to be used for a variety of purposes such as an information 60 signal to an engineer for indicating that the grade crossing signal has properly operated, a block signal and a signal for an open switch, broken rails or the like.

With these and other objects in view the 65 invention consists in the construction and novel combination and arrangement of parts hereinafter fully described, illustrated in the accompanying drawings and pointed out in the claims hereto appended, it being 70 understood that various changes in the form, proportion and minor details of construction may be resorted to without departing from the spirit or sacrificing any of the advantages of the invention. 75

In the drawing—

Figure 1 is a perspective view of a grade crossing signal constructed in accordance with this invention,

Fig. 2 is a horizontal sectional view of the 80 same,

Fig. 3 is a vertical sectional view on the line 3—3 of Fig. 2,

Fig. 4 is a vertical sectional view on the line 4—4 of Fig. 2, 85

Fig. 5 is a detail view of the blade carrying arm of the electric switch.

Fig. 6 is a sectional view on the line 6—6 of Fig. 2,

Fig. 7 is a plan view of a signal showing 90 another form of the invention,

Fig. 8 is a vertical sectional view of the same.

Like numerals of reference designate corresponding parts in all the figures of the 95 drawings.

In the accompanying drawings in which is illustrated the preferred embodiment of the invention, 1 designates a casing or box constructed of any suitable material and 100 mounted upon a pole 2. The lower end of the box or casing receives the upper end of the pole and is secured to the same by a horizontal bolt 3 or other suitable fastening means and one or more bolts may of course 105 be employed.

The box or casing which is preferably rectangular in cross section but which may be made of any other configuration is divided 110 into a vertical series of chambers or com-

partments by horizontal partitions 4, 5, 6, 7, and 8 and the said casing is also provided with a top 9 which may be pointed as shown or any other shape and which when pointed 5 provides a space above the partition 8 into which extends the upper portion 10 of a vertically movable rack bar 11 when the latter is at the limit of its upward movement. The rack bar which is vertically disposed is also 10 provided with a straight lower portion 11^a and the said upper and lower portions are guided in openings in the partitions through which they pass so that the rack bar will be held steady and true in its vertical sliding 15 movement. The rack bar is equipped at its lower end with a piston head 12 operating in a vertical cylinder 13 located in the bottom compartment 14 and provided at its lower end with an inwardly opening valve 15 20 adapted to permit the air to enter the cylinder 13 freely during the upward movement of the rack bar when the same is actuated by a motor 16. The cylinder is also provided at opposite sides with four vent 25 ports 17 which permit the slow escape of air from the cylinder when the power is cut off from the motor and the rack bar descends by gravity. This produces a slow movement of the signal to its initial position after it has 30 been operated. The cylinder 13 extends from the top to the bottom of the compartment 14 but it may of course be of any desired length to accommodate itself to the stroke of the rack bar. The rack bar is 35 equipped at three of its sides with spur teeth 18, 19, and 20 which mesh with an actuating pinion 21, a toothed quadrant or gear element 22 and a pinion 23 which also meshes with a toothed quadrant for reversing 40 the motion to cause the quadrant 24 to move in the opposite direction to the quadrant 22 which directly meshes with the rack bar. By this construction, the semaphore arms 25 and 26, which are connected with 45 the quadrants, are simultaneously moved in opposite directions and when one of the arms is swung upwardly from a depending vertical position the other will be swung downwardly from a horizontal position to a 50 vertical position and vice versa. The actuating pinion 21 is connected by a train of gears with the motor 16 and is mounted on a shaft 27 extending through one side of a casing 28 which is mounted in an intermediate 55 compartment 29 located between the partitions 5 and 6 and preferably of a greater size than the other compartments to accommodate the gearing and the casing and the motor. The shaft 27 which is journaled at 60 its inner end in a vertical support 30 has keyed or otherwise secured to it a gear wheel 31 which meshes with a pinion 32 of an upper horizontal shaft 33 journaled in and extending through the support 30 and 65 provided at the opposite side thereof with a

gear wheel 34 which meshes with a pinion 35 of a countershaft 36. The counter shaft 36 is journaled at its outer end in one of the sides of the casing or gear case and its inner end is journaled in the said support 30 70 which is of sufficient thickness to enable the countershaft and the shaft 27 to have their adjacent ends journaled in sockets or bearings in its opposite faces. The gear case 28 is suitably supported by standards or posts 75 37 and the counter shaft carries a gear wheel 38 which meshes with a pinion 39 of the motor shaft 40 but any other suitable means may of course be employed for connecting the motor with the train of gears which 80 actuate the rack bar in the vertical movement thereof.

In practice, a small motor of the toy type will be sufficient to raise the rack bar owing to the counter-balancing of the parts through 85 the semaphore arm and the train of gears which may be composed of pinions and gear wheels of any relative diameters cut down the speed of the motor to a slow movement of the rack bar and furnishes ample power 90 for the same. When the current is thrown on the motor the actuating pinion is rotated by the train of gears connecting it with the motor and the rack bar is moved upwardly to its elevated position and as soon as the 95 current is cut off from the motor the rack bar descends by gravity its downward movement being retarded by the air contained within the cylinder 13. The air escapes slowly through the vent ports 17 at the lower 100 end of the cylinder and permits a slow downward movement of the rack bar which carries a lamp supporting frame 41 and moves the same from an upper light receiving compartment 43 to a lower light receiving 105 compartment 42. The light supporting frame which is in the form of a cage is provided at the bottom with a platform 44 and an upper plate 45 adapted to close or cover an opening 46 in the partition 7 when the 110 rack bar is in its lower or initial position. The lamp supporting frame is composed of the plates 44 and 45 and vertical connecting portions which are arranged out of the lines intersecting central bull's-eyes 47 and 48 and 115 a lamp 49. Each of the walls of each of the light receiving compartments is provided with an aperture and a bull's-eye, two of the bull's-eyes being designed to be red and two white but any other signaling colors may of course be employed.

These bull's-eyes are arranged so that when the lamp is in the lower compartment a red light will be shown to the track and a white light to the roadway and vice versa 125 when the lamp is located in the upper light receiving compartment. When the lamp is in the lower light receiving compartment the upper plate 45 by closing or covering the opening 46 prevents any illumination 130

of the upper light receiving compartment so that the light thereof will not show until the lamp is carried upward into the said compartment 43. While a lamp is shown arranged upon the platform or bottom plate 44 in the accompanying drawings, an electric light may of course be used and may be hung from the top plate and the slow movement of the rack bar through the air cylinder will prevent a sudden downward movement of the rack bar from extinguishing the lamp. When the rack bar is at the limit of its upward movement the lower plate or platform 44 fills the opening 46 and prevents any illumination of the lower compartment 42. When the rack bar is in its lower position, the arm 25 which is connected with the shaft 49 upon which the toothed quadrant 22 is secured, is arranged in a horizontal position and extends across the track for stopping a train and it will be clear that should anything happen to the train blocking system such as a failure of current or the like gravity will cause the rack bar to descend and elevate the semaphore arm 25 which holds up the train so that the latter will be prevented from proceeding. Also it will be clear that when the semaphore arm controlling the road is down, persons may cross in perfect safety as it will be impossible for the train to proceed without passing under the semaphore arm 25. The shaft 49 is journaled in suitable bearings of the casing 1 and extends through one of the walls thereof as clearly shown in Fig. 2 of the drawings.

The other semaphore arm 26 is mounted on a horizontal shaft 50 extending through one of the sides of the casing 1 and having mounted on it the quadrant 24 which meshes with the said pinion 23 and the latter is suitably mounted on a shaft 51. While toothed quadrants are shown complete gears may also be employed but a quadrant is preferable as it will enable a casing of less size to be employed for containing the mechanism. The casing is provided at the bottom partition 4 with an opening 52 and is spaced from the upper end of the post or pole 2 to provide an air space 53 which communicates with the outside atmosphere through an aperture 54. Any other suitable means may of course be employed for connecting the valve 15 with the atmosphere. The vertically movable rack bar carries a rigid horizontally disposed switch arm 55 provided with a series of insulated metallic blades 56 adapted to be moved into engagement with upper and lower contacts 57 and 58 arranged in pairs and forming a slidable contact. The upper and lower contacts 57 and 58 which are connected with the wires 59 and 60 of a plurality of circuits consist of resilient plates arranged in pairs and having their outer terminals flared slightly

to form an entrance and a sliding frictional engagement between the blades of the switch arm and the contact plates provide a bright, clean electrical contact and insure an operation of the circuits controlled by the signal. 70 When the signal is in its initial position, the lower circuits are closed and when the signal through an operation of the motor is moved to its other signaling position the lower circuits are opened and the upper circuits 75 are closed. This construction makes it possible for one train to obtain the control over other trains as the controlling circuit of each train may be through the signal of the other train and constitute one of the 80 lower circuits in order that such circuit will be broken when the switch arm is moved from the lower to the upper position.

Any number of electric circuits may be controlled in this manner and the casing 1 may be equipped with an auxiliary rack bar 60^a vertically movable in suitable guides 61 and carrying a horizontally disposed switch arm 62 having a blade 63 arranged to close upper 90 and lower circuits 64 and 65. Any number of such circuits may of course be employed and the rack bar 60 meshes with an actuating pinion 66 connected by a train of gears 67 with a pinion 68 of a shaft 69 of a motor 95 70. The gearing is similar to that heretofore described but may of course be composed of any desired number of pinions and gear wheels and it is mounted in a suitable gear casing 71. While it is unnecessary to 100 employ an air cylinder for controlling the downward movement of the auxiliary rack bar 60 any suitable means may be provided for this purpose, if desired.

The signal illustrated in Figs. 1 to 6 inclusive is designed for a grade crossing signal but the mechanism may be employed for various kinds of signals such as block signals, broken rails and open switch signals and the like and when only one semaphore 110 arm is desired or necessary, it may be counter-balanced by a stub arm 72. In signals of this type the semaphore arm 73 is arranged in a horizontal position when the rack bar is in its lowered position when the said signal is used in a closed circuit so that in event of the breaking of the circuit the semaphore arm 73 will be carried upward to a horizontal position by the gravity action of the mechanism. The rack bar 74 is similar in 115 construction to that heretofore described and it carries horizontally disposed switch arms 75 and 76 provided with blades 77 and 78 for closing the circuits of upper and lower contact plates 79 and 80. Any number 120 of the upper and lower circuits may of course be employed to secure the desired control of the mechanism to be operated.

The semaphore arm 73 is connected with a segment 81 which meshes with the rack 130

bar 74 and the latter is actuated by a pinion 82. The counter-balancing stub arm 72 is connected with the rack bar by the means employed for connecting the semaphore arm 26 hereinbefore described and as this gearing is clearly illustrated in Fig. 4 of the drawings, further illustration thereof is believed to be unnecessary.

What is claimed is:—

- 10 1. In a signaling means, a casing provided adjacent its upper end with an upper light receiving compartment and a lower light receiving compartment disposed in superposed relation, said compartments being separated by a centrally apertured partition member and having signaling closure members secured in their opposite walls, a rack bar mounted axially of the casing for vertical sliding movement therein, a lamp housing carried by said bar and provided with top and bottom plates adapted to close the opening through said partition member when the bar is moved into its extreme position in either direction, a lamp mounted in said housing for illuminating said compartment, signaling arms rockably mounted on the casing for movement about horizontal axes in planes at right angles to each other, and connections between said arms and the rack bar for causing simultaneous operation of the arms in opposite directions when the rack bar is operated, the movement of the bar serving to move the lamp into one of the light receiving compartments so as to produce an illuminated signal corresponding to the signal given by said arms.
- 20 2. In signaling means, a casing of sub-
- 25
- 30
- 35

stantial rectangular cross section provided with a plurality of spaced horizontal partition members, the partition members at the upper end of the casing forming two light receiving compartments, each of said compartments being provided with openings through its walls and signaling closure members secured therein, a rack bar mounted coaxially with the casing and slidable through the partition members thereof so as to be braced and guided thereby, a lamp supported directly by said bar so as to be moved from one of the light receiving compartments to the other in accordance with movement of the bar, a lamp housing carried by the bar and having top and bottom plates for closing the openings through the partition between the light receiving compartments, signaling arms rockably mounted on the casing for movement about horizontal axes in planes at right angles to each other, and connections between said arms and the rack bar for simultaneously moving the arms in opposite directions when the rack bar is operated, the operation of the rack bar serving to move the lamp into position to illuminate one of the light receiving compartments so as to produce an illuminating signal corresponding to the signal given by said arms.

In testimony whereof I affix my signature in presence of two witnesses.

SAMUEL L. NEELY.
